COMBINED EXTERIOR LAMP AND FILTER FOR SMALL POOLS

Makoto Yamazaki, 10-16 Chuo 5-chome, Ota-ku,
Tokyo, Japan

Filed Aug. 22, 1969, Ser. No. 18,802

Term of patent 14 years

Int. Cl. D23—01; D26—03

U.S. Cl. D23—4

FIG. 1

FIG. 2

FIG. 3

FIG. 5

FIG. 4

FIG. 6

FIG. 1 is a perspective view of the combined exterior lamp and filter for small pools showing my new design.

FIG. 2 is a front view thereof.

FIG. 3 is a top view thereof.

FIG. 4 is a right side view thereof.

FIG. 5 is a rear view thereof.

FIG. 6 is a bottom view thereof.

I claim:

The ornamental design for combined exterior lamp and filter for small pools, as shown.
